US0D1051745S

(12) **United States Design Patent** (10) Patent No.: **US D1,051,745 S**
(45) Date of Patent: ** Nov. 19, 2024

(54) **WEARABLE SENSOR**

(71) Applicant: **Bioliniq Incorporated**, San Diego, CA (US)

(72) Inventor: **David Michael Morelock**, Escondido, CA (US)

(73) Assignee: **Bioliniq Incorporated**, San Diego, CA (US)

(**) Term: **15 Years**

(21) Appl. No.: **29/890,886**

(22) Filed: **Apr. 27, 2023**

Related U.S. Application Data

(62) Division of application No. 29/836,984, filed on Apr. 29, 2022, now Pat. No. Des. 1,013,544.

CLAIM

The ornamental design for a wearable sensor, as shown and described.

DESCRIPTION

FIG. 1 is a front perspective view of a wearable sensor showing the new design;
FIG. 2 is a front view thereof;
FIG. 3 is a top plan view thereof;
FIG. 4 is a bottom plan view thereof;
FIG. 5 is a left side view thereof;
FIG. 6 is a right side view thereof;
FIG. 7 is a rear view thereof;
FIG. 8 is a front perspective view of another wearable sensor showing the new design;
FIG. 9 is a front view thereof;
FIG. 10 is a top plan view thereof;
FIG. 11 is a bottom plan view thereof;
FIG. 12 is a left side view thereof;
FIG. 13 is a right side view thereof;
FIG. 14 is a rear view thereof;
FIG. 15 is a front perspective view of another wearable sensor showing the new design;
FIG. 16 is a front view thereof;
FIG. 17 is a top plan view thereof;
FIG. 18 is a bottom plan view thereof;
FIG. 19 is a left side view thereof;
FIG. 20 is a right side view thereof;
FIG. 21 is a rear view thereof;
FIG. 22 is a front perspective view of another wearable sensor showing the new design;
FIG. 23 is a front view thereof;
FIG. 24 is a top plan view thereof;
FIG. 25 is a bottom plan view thereof;
FIG. 26 is a left side view thereof;
FIG. 27 is a right side view thereof;
FIG. 28 is a rear view thereof;
FIG. 29 is a front perspective view of another wearable sensor showing the new design;
FIG. 30 is a front view thereof;
FIG. 31 is a top plan view thereof;
FIG. 32 is a bottom plan view thereof;
FIG. 33 is a left side view thereof;
FIG. 34 is a right side view thereof;
FIG. 35 is a rear view thereof;
FIG. 36 is a front perspective view of another wearable sensor showing the new design;

FIG. 37 is a front view thereof;
FIG. 38 is a top plan view thereof;
FIG. 39 is a bottom plan view thereof;
FIG. 40 is a left side view thereof;
FIG. 41 is a right side view thereof;
FIG. 42 is a rear view thereof;
FIG. 43 is a front perspective view of another wearable sensor showing the new design;
FIG. 44 is a front view thereof;
FIG. 45 is a top plan view thereof;
FIG. 46 is a bottom plan view thereof;
FIG. 47 is a left side view thereof;
FIG. 48 is a right side view thereof;
FIG. 49 is a rear view thereof;
FIG. 50 is a front perspective view of another wearable sensor showing the new design;
FIG. 51 is a front view thereof;
FIG. 52 is a top plan view thereof;
FIG. 53 is a bottom plan view thereof;
FIG. 54 is a left side view thereof;
FIG. 55 is a right side view thereof;
FIG. 56 is a rear view thereof;
FIG. 57 is a front perspective view of another wearable sensor showing the new design;
FIG. 58 is a front view thereof;
FIG. 59 is a top plan view thereof;
FIG. 60 is a bottom plan view thereof;
FIG. 61 is a left side view thereof;
FIG. 62 is a right side view thereof;
FIG. 63 is a rear view thereof;
FIG. 64 is a front perspective view of another wearable sensor showing the new design;
FIG. 65 is a front view thereof;
FIG. 66 is a top plan view thereof;
FIG. 67 is a bottom plan view thereof;
FIG. 68 is a left side view thereof;
FIG. 69 is a right side view thereof;
FIG. 70 is a rear view thereof;
FIG. 71 is a front perspective view of another wearable sensor showing the new design;
FIG. 72 is a front view thereof;
FIG. 73 is a top plan view thereof;
FIG. 74 is a bottom plan view thereof;
FIG. 75 is a left side view thereof;
FIG. 76 is a right side view thereof; and,
FIG. 77 is a rear view thereof.

The broken lines are for the purpose of illustrating portions of the article and form no part of the claimed design.
